J. A. MILLER

ENAMELING OVEN

Filed Nov. 14, 1921

Inventor

John A. Miller
By his Attorneys
Blackstone, Spencer & Blodget.

UNITED STATES PATENT OFFICE.

JOHN A. MILLER, OF TARRYTOWN, NEW YORK.

ENAMELING OVEN.

Application filed November 14, 1921. Serial No. 515,160.

To all whom it may concern:

Be it known that I, JOHN A. MILLER, a citizen of the United States of America, and a resident of Tarrytown, county of Westchester, and State of New York, have invented certain new and useful Improvements in Enameling Ovens, of which the following is a full, clear, concise, and exact description, such as will enable others skilled in the art to which the invention relates to make and use the same, reference being made therein to the accompanying drawings, which form a part of this specification.

This invention relates in general to heat-treating ovens or ovens for drying or baking a protective coating on metallic articles and other objects and more particularly to a ventilating system therefor.

One of the objects of the invention is the provision of means for uniformly heating and drying or baking the protective coating on vehicles, parts thereof, and other objects that have been subjected to a coating process.

Another object of the invention is the provision of means for removing the gases, odors, and impurities incident to the drying or baking of the coating during the drying or baking operation without materially interfering with or detracting from, the efficiency of the heating arrangement.

A still further object of the invention is the provision of a baking oven that is cheap to manufacture, easily assembled, is composed of few parts, that is simple in construction and not likely to get out of order.

Other and further objects of the invention will appear as the description proceeds.

On the drawing:

Figure 1 is a side elevation of the oven with parts in section and parts broken away;

Figure 2 is a front elevation of the same with parts in section and parts broken away.

In ovens for drying or baking protective coatings on vehicle bodies and parts thereof it has been heretofore the custom to employ ovens of large productive capacity. In other words, drying or baking ovens of this nature have been employed almost exclusively by manufacturers and others doing the original painting, varnishing or enameling of vehicles in quantity.

The present invention contemplates the employment of a small oven which is especially adapted to be employed in garages or by others doing a recoating business. It is evident, however, that the device is not so

limited in its use, but may be employed for drying or baking original coatings on vehicles or other articles and treating them on an extensive scale.

For the purpose of simplicity of illustration and convenience of description, a device is shown more or less diagrammatically that is adapted to accommodate a single vehicle body and parts thereof.

On the drawing, the reference numeral 10 designates a support such as the floor of a garage or other building. The floor is usually made of concrete and mounted thereon is the bottom wall or floor 11 of the oven. This floor may be made from any suitable material, such as from the commercial magnesia block. The floor 11 supports and has attached thereto the rear end wall 13 and the side walls 14. The top wall 15 is secured to, and supported by, the end and side walls. The front end wall comprises two doors 16 and 17 which are hinged to the supports 18 secured to the front ends of the side walls 14. The free edge of the door 16 is provided with an extension 19 which is adapted to overlap the free edge of the door 17 when the doors are in closed position to seal the joints between the meeting edges of the two doors.

Any suitable latching means may be provided for securing the doors in closed position. As shown on the drawing, the free edge of the door 16 is provided with the pivoted latch 19' which has attached thereto the longitudinally movable latch bolts 20, 21 which are adapted to engage keepers 22 and 23 secured to the top and bottom walls, respectively.

While I have shown the oven as being rectangular in form and of comparatively small dimensions it is to be understood that it may be of any suitable form and dimensions.

Attached to the rear wall adjacent the floor of the oven is an air chamber 24 of any suitable form and material. As shown on the drawing, the air chamber is rectangular in form and may be made from sheet metal and extends the full length of one dimension of the oven as across the rear end thereof. The chamber 24 is divided into an upper air inlet chamber 25 and a lower ventilating chamber 26. The partition 27 that divides the chambers 25 and 26 is in the form of an inverted V with a very broad base. By this arrangement sufficient spaces are provided for a large air outlet in the

middle portion of the rear wall of the lower chamber and a large air inlet in each end of the front wall of the upper chamber, without unduly increasing the dimensions of the 5 air chamber. In order to insure uniform ventilation across the entire width of the oven, the ventilating chamber 26 is provided along the lower portion of its front wall with the inlet apertures or openings 28 extending the full length of the chamber. The 10 chamber is also provided in its rear wall at the center thereof with a large outlet opening 29 the area of which must be at least as large as the combined areas of the 15 ventilating openings 28. A ventilating pipe or conduit 30 is secured about the opening 29 and has the extension 31 extending upwardly therefrom for creating a draft and for conducting away the obnoxious gases. The extension 31 may be, and preferably is, provided with a valve 32 which may be held in adjusted position by any suitable means. As shown, the lever 33, which is rigidly secured to the valve pivot is adapted to be 25 adjusted by means of a bolt or rod 33^a which, in turn may be held in adjusted position by means of a set screw, 33^b, in the usual manner.

The valve 32 is provided with a small central opening in order to provide for a certain amount of ventilation even though the valve be entirely closed.

For the purpose of rapidly clearing and cooling the oven or, under certain conditions, for regulating the heat thereof, an ar- 30 euate pipe or passage 35 extending through the top wall and communicating with the extension 31 may be provided. This pipe is adapted to be closed by the manually oper- 35 ated valve 36 during the normal operation of the oven. The valve 36 may be held in adjusted position by any suitable means such as the set screw 36' engaging the link 38 which operates the valve crank arm 39.

In order to insure equal distribution of the air in passing into the oven, the top wall of the air intake chamber 25 is provided with a series of outlet openings or apertures 37 extending the full length of the chamber. 40

The chamber 25 is also provided with large air inlet openings 40 and 41 in its rear wall adjacent each end thereof. The combined areas of the large openings 40 and 41 must be at least as large as the combined areas of 45 the small openings 37. Hollow members 42 and 43 secured about the openings 40 and 41 extend through the rear wall 13 and thus place the air chamber in communication with the external atmosphere.

A series of suitable heating devices are 50 arranged at the rear of the oven above the air chamber 25 in such a position that the air ascending from the air chamber 25 will pass about the heating elements and become heated to the desired temperature. Any 55

suitable form of heating element or elements may be employed and they may be supported in any suitable or convenient manner. As shown on the drawings, a series of electrical heaters 44 are employed.

The top wall 15 may be provided with any suitable form and number of supporting elements 45 for supporting fenders 46 or other articles during the drying or baking operation.

In the operation of the device, if an automobile body is to be treated, the body is removed from the chassis, and its fenders, etc. are removed. The body 47 is mounted on a suitable supporting means such as the truck 48, and after the protective coating has been applied to the body and its parts, the truck 48 is run into the oven 12. The fenders and other parts are properly suspended from the supports 45 after which the doors 16 and 17 are secured in closed position. The heat is now turned on and the air from the outside entering through the apertures 40 and 41 into the air chamber 25 passes upwardly through the outlet openings 37 and ascending about the heaters 44 is heated to the desired temperature, circulates about the coated articles for drying or baking the same. Parts of the air and obnoxious gases continually escape through the pipe 30 and its extension 31, and by adjusting the valve 32 the circulation of air within the oven 12 may be regulated and the noxious gases removed without materially interfering with the baking operation.

By means of this device it is possible to refinish automobile bodies and parts thereof without removing the upholstery, since by means of this arrangement it is not necessary to heat the oven above the point where it would injure the upholstery, say 250 to 260 degrees F. depending on the material of the upholstery.

While the device is primarily intended for baking enamel on vehicles, parts thereof, and other articles, it is understood that the device may be employed to dry paint, varnish and similar coatings employing lower temperatures than is required for enameling work.

It will thus be seen that I have provided a drying or baking oven that is cheap to manufacture and efficient in operation and one that may be installed in almost any garage for the purpose of recoating automobiles and parts thereof.

I claim:

1. In a heat treating device of the class described, a chamber having an entrance leading thereto, and a closure for said entrance, heating means located within said chamber, an air intake device located within said chamber in direct communication with the exterior atmosphere through an opening provided in the wall of said chamber

- and discharging directly into the interior of said chamber adjacent the lower portion thereof, said chamber being provided in one of its walls adjacent the lower end thereof with a ventilating opening communicating with said air intake device, and a ventilating conduit communicating with said opening and extending upwardly therefrom.
2. In a device of the class described, a chamber provided with an entrance opening leading thereto, and a closure for said opening; an air intake device located within the lower portion of said chamber and adjacent the wall thereof opposite said opening, said air intake device being in communication with the external atmosphere, and having a plurality of air inlets discharging directly into said chamber, and said distributing device having a plurality of ventilating openings leading directly into the interior of said chamber and through which openings gases may flow from the interior of said chamber into said air intake device and from said device through an opening in the wall aforesaid, a conduit through which gases escaping from the interior of said chamber as aforesaid may flow, a valve for controlling the flow through said conduit, and heating means located adjacent the wall of said chamber opposite the opening leading thereto, and above said air intake device.
3. In a device of the class described, an air chamber for a heat treating device, said chamber consisting of an upper air inlet chamber and a lower ventilating chamber, said air inlet chamber having openings therein for permitting a uniform flow of air therefrom along substantially the entire length of one dimension thereof, and having other openings for permitting a uniform flow of gases into said ventilating chamber along substantially the full length of one dimension of said ventilating chamber.
4. An air chamber, an inverted V-shaped partition dividing said chamber into an upper compartment and a lower compartment, the upper wall of said chamber provided with a series of apertures extending substantially the full length thereof, the rear wall of said upper compartment provided with a large opening at each end thereof, the front wall of said lower compartment provided with a series of apertures extending substantially the full length thereof and the rear wall of said lower compartment provided at its widest portion with a large opening, substantially as shown and described.
5. In a device of the class described, a chamber, means for heating the same, means adjacent the lower portion of one side wall of said chamber for admitting air to said chamber, means below the air admission means and adjacent a still lower portion of said side wall of said chamber for permitting the escape of air and gases from said chamber, including a conduit for conducting said air and gases away from said chamber, a passage connecting the upper portion of said chamber and conduit, and a valve in said passage.
6. In a heat treating device of the class described, a chamber having an entrance opening at one end thereof, and a closure for said opening; heating means located within said chamber and adjacent the wall thereof opposite said opening; and an air intake device leading from the external atmosphere through the lower portion of the wall aforesaid and discharging directly into said chamber; said chamber being provided adjacent the lower end thereof with a ventilating outlet opening.
7. In a device of the class described, a chamber having doors at one side thereof, and heating and ventilating means adjacent to another side thereof comprising air inlet means and air outlet means arranged low down along said last named side, the former above the latter, and a second air outlet means from the top of the chamber and an air heater substantially above the air inlet means.
8. In a device of the class described, a chamber having doors at one side thereof, and heating and ventilating means adjacent to another side thereof comprising air inlet means and air outlet means arranged low down along said last named side, the former above the latter, and a second air outlet means from the top of the chamber and an air heater substantially above the air inlet means, both said air outlet means being connected together outside the chamber.

In testimony whereof I affix my signature.

JOHN A. MILLER.
